UNITED STATES PATENT OFFICE.

OSCAR L. NEISLER, OF CHICAGO, ILLINOIS.

INTERNAL-COMBUSTION ENGINE.

1,110,386.

Specification of Letters Patent. Patented Sept. 15, 1914.

Application filed March 7, 1913. Serial No. 752,560.

To all whom it may concern:

Be it known that I, OSCAR L. NEISLER, citizen of the United States, residing at Chicago, in the county of Cook and State of Illinois, have invented certain new and useful Improvements in Internal-Combustion Engines; and I do hereby declare the following to be a full, clear, and exact description of the invention, such as will enable others skilled in the art to which it appertains to make and use the same.

My invention relates to internal combustion or explosion engines and more particularly to two-cycle engines. Its prime objects are to provide a simple and positive mechanism for drawing the charge into a compression chamber, for compressing this charge and for delivering it to the ignition or power cylinder under pressure.

A further object is to time the admission of the charge to the cylinder and the emission of the exhaust from the same in proper relation to the stroke of the engine, thereby eliminating any waste of charges and the unsteadiness of operation commonly due to an improper timing of the exhaust relative to the intake.

Still another object of my invention is to house the entire operating mechanism within the casing of the engine, thereby avoiding the danger of a tampering with this mechanism and also enabling the engine to withstand outward abuse.

I accomplish these objects by the construction shown in the accompanying drawings, in which—

Figure —1— is a central vertical section through a two-cylinder engine embodying my invention. Fig. —2— is a vertical section through Fig. —1— along the line 2—2. Fig. —3— is a horizontal section through Fig. —1— along the line 3—3. Fig. —4— is a horizontal section through Fig. —1— along the line 4—4.

In the drawings, the cylindrical casing 1 has in its upper portion an inner cylinder 2 connected to the casing 1 by upper and lower annular portions 3 and 4, whereby a water-jacket chamber 5 is provided around the cylinder 2. This chamber 5 is also preferably connected by openings 32 to a chamber 31 for water-jacketing the upper end of the cylinder. Below the lower end 4 of the water jacket or cooling chamber 5, the casing 1 is bored to fit an enlarged annular

piston 6 terminating in a hollow cylindrical extension portion 7 which fits the main cylinder 2 of the engine and which constitutes the cylinder within which the power piston 8 of the engine is actuated. The piston 8 is connected to a crank-shaft 9 by a pitman 10 having engagement with a pin 11 mounted within the power piston 8. The crank-shaft 9 is journaled in bearings 12 upon the casing 1 of the engine and has eccentrics 13 upon its shaft on opposite sides of the crank 14, which eccentrics are connected to opposite sides of the annular piston 6 by rods 15. The eccentrics 13 are preferably positioned upon the shaft at about one hundred eighty degrees from the crank 14, but this relation may be varied as desired.

The head 16 of the inner cylinder 2 has a reentrant formation 17 projecting into the upper end of the cylinder 2, thereby forming an annular passage 18 into which the upper end of the cylindrical extension portion 7 may move considerably beyond the lower end 19 of the reentrant head formation. Exhaust ports 20 in the wall of the cylinder 2 adjacent to this head 19 communicate with exhaust passages 21, these ports 20 being adapted to register with discharge ports 22 in the portion 7 when the latter is at the uppermost position of its travel. Adjacent to its juncture with the annular piston 6, the portion 7 is reduced in diameter, thereby providing an annular space or groove 23 between the lower portion of the portion 7 and the cylinder 2 when the former is at or near its uppermost position. Inlet ports 24 in the portion 7 connect the interior of the same with the upper end of the annular space 23 thus formed between the opposed peripheral walls of the cylinder and the valve portion 7 adjacent to the juncture of the differently sized parts of the cylinder. These ports 24 are normally covered by the outer surface of the power piston 8, but are uncovered for a brief interval of time while the piston 8 is passing the lowest point of its travel.

When the portion 7 is in its uppermost position, the upper end of its piston portion 6 does not abut against the lower end 4 of the water-jacket chamber 5, but still leaves an annular chamber 26 between the two, of which chamber the annular space 23 forms a part, constituting a connecting duct to the ports 24. The chamber 26 as thus formed

between the opposed shoulders of the parts of larger diameter of the cylinder and the reciprocating hollow member is increased in size as the piston 6 descends, and is adapted to receive the gaseous charge for the engine through an intake port 27 which is uncovered by the piston 6 when the latter is at the lower limit of its travel. Packing rings 28, provide tight joints between the several 10 interfitting and relatively reciprocating parts. A spark plug 29 is located in the head 19 for igniting the charge after this has been admitted to the combustion chamber formed coactively by the piston, the 15 cylinder head and the sliding member 7. With multi-cylinder engines, the above-described elements are found in each of the cylinders connected to the same shaft.

In operation, the mixture of gas and air 20 in the combustion chamber 30 of the cylinder is ignited by the spark plug 29 when the piston 8 is at or near the uppermost or most outward point of its travel (as shown in the right hand portion of Fig. —1—) at 25 which time the extension portion 7 of the piston 6 closes the exhaust ports 20. At the same time the piston 6 has passed and uncovered the intake port 27, through which a mixture of gas and air freely enters the 30 initial charge compressing spaces 26 and 23. When the charge is ignited in the cylinder, the piston 8 is moved inwardly thereby causing the pitman 10 to rotate the shaft 9, which in turn moves the eccentrics 13 and 35 through the rods 15 propels the piston 6 and its extension portion or valve-sleeve 7 in an upward direction. As soon as the upper end of the piston 6 passes the top of the intake port 27, it cuts off the combustible fluid 40 supply and the further upward movement of the said piston 6 compresses the gaseous mixture in the spaces 26 and 23. This compression continues until the piston 8 uncovers the inlet ports 24 (as shown in the 45 left hand half of Fig. —1—, and as also shown in Fig. —2—) when the compressed charge is admitted under pressure through these piston-controlled inlet ports into the interior of the cylinder. By the time this 50 occurs, the valve member 7 has moved upward so that the discharge ports 22 register with the exhaust ports 20, allowing the gaseous products left in the cylinder from the previous explosion to pass out into the exhaust passage 21. Then when the crank 14 has passed its lowermost position, the momentum of the moving parts of the engine will continue to rotate the shaft; thereby moving the piston 6 and its sleeve 7 downward, while the piston 8 moved upward and closes the inlet ports 24. At the same time, the downward motion of the valve sleeve 7 will carry the discharge ports 22 out of registry with the exhaust ports 20, 55 thereby leaving the fresh charge entrapped

in the interior 30 of the cylinder when it will be compressed as the piston 8 moves upward.

Meanwhile, the closing of the inlet ports 24 by the power piston 8 will disconnect the 70 chamber 26 and its extension 23 from the combustion chamber 30 of the cylinder, leaving this compressing space filled with a small amount of the initial charge. Then as the annular compression piston 6 descends, this space is greatly increased in size, thereby attenuating the gaseous mixture in the same. Consequently, when the moving parts reach the positions at which the intake port 27 is again opened, there will be a partial vacuum in the spaces 26 and 23 and this partial vacuum will cause a fresh charge to be instantly sucked in through the intake port.

Thus, the engine of my invention will 85 draw the charge rapidly into its initial compression chamber, compress the charge therein, deliver the charge under pressure 90 into the power cylinder (thereby enabling it effectively to displace the residual burnt gases in this cylinder), and then compress the charge in the cylinder and ignite the same while under pressure.

While I have shown and described my invention as embodied in a two-cylinder engine, I do not wish to be limited to the twin form, nor to the precise details as set forth in this embodiment, it being obvious that numerous changes may be made in the same without departing from the spirit of my invention.

I claim as my invention:

1. An internal combustion engine comprising a cylinder of different diameters at respectively opposite ends, a head for the smaller end of said cylinder, the larger end thereof being open, a tubular member fitting the smaller end of said cylinder and having an annular piston flange fitting the larger end thereof, exhaust ports in the wall of 105 the smaller end of the cylinder adapted to register with exhaust openings in said tubular member as the latter reaches the limit of its stroke into said smaller end of said cylinder, said piston flange coacting with the shoulder at the inner end of the larger end portion of the cylinder to provide a charge compression chamber, inlet ports in said tubular member adapted to pass said shoulder as said member reciprocates, a trunk piston for said tubular member controlling said inlet ports and adapted to open the same to admit a charge from said compression chamber while said exhaust openings register with the exhaust ports and as said trunk 110 piston attains the outer limit of its movement, there being a passage in the inner wall of the smaller end of said cylinder extending from said shoulder to the point to which the inlet ports travel for maintaining 115

the latter in communication with said compression chamber.

2. In an internal combustion engine, a cylinder having its respective ends of different diameters and affording an annular abutment between the parts of different diameter, a tubular member fitting the smaller end of said cylinder and having an annular piston flange fitting the larger end and coacting with said abutment to provide a charge compressing chamber, a trunk piston within said member, a crank shaft having two diametrically opposed cranks and connected with said member and said trunk piston 10 ton respectively for simultaneously reciprocating the latter in respectively opposite directions, a head for the smaller end of such cylinder, there being exhaust openings in the circumferential wall of the 15 smaller end of the latter and in the said

tubular member arranged to register as said tubular member attains the inner limit of its movement, there being inlet openings in said tubular member controlled by said trunk piston and uncovered by the latter as 25 it reaches the outer limit of its movement and while said exhaust ports are open, there being a passage for the compressed charge from the compressing chamber to point of location of said inlet ports relatively to the 30 smaller end of the cylinder when the same are uncovered by said piston.

In testimony whereof I have signed my name in presence of two subscribing witnesses.

OSCAR L. NEISLER.
